(74) Attorney, Agent, or Firm—Jeffer, Mangels, Butler & Marmaro, LLP

(57) **CLAIM**

The ornamental design for a container cap, as shown and described.

DESCRIPTION

FIG. 1 is a front elevational view of the cap of the present invention, the rear, left and right side elevational views being the same as the front elevational view.

FIG. 2 is a top plan view of FIG. 1; and,

FIG. 3 is a bottom plan view of FIG. 1.

The broken line showing of a container is for illustrative purposes only and forms no part of the claimed design.

1 Claim, 1 Drawing SheetFIG. 1

FIG. 2

FIG. 3

UNITED STATES PATENT AND TRADEMARK OFFICE
CERTIFICATE OF CORRECTION

PATENT NO. : Des. 462,905 S
DATED : September 17, 2002
INVENTOR(S) : Howard Siegel and Anthony Jordan
